UNITED STATES PATENT OFFICE.

WILLIAM C. DILLINGHAM, OF BAIRDSTOWN, CALIFORNIA; CHARLES H. DILLINGHAM
ADMINISTRATOR OF SAID WILLIAM C. DILLINGHAM, DECEASED.

WAITER AND SALES CHECK.

1,356,050.

Specification of Letters Patent.

Patented Oct. 19, 1920.

Application filed April 28, 1913. Serial No. 764,273.

To all whom it may concern:

Be it known that I, WILLIAM C. DILLINGHAM, a citizen of the United States, residing at Bairdstown, in the county of Los Angeles and State of California, have invented a new and useful Waiter and Sales Check, of which the following is a specification.

This invention is designed for the use, 10 convenience and safety of a proprietor and his agents in keeping check and account of sales and may be used in restaurants, barber shops, stores and other places of business wherever the conditions to which it is fitted 15 exist.

That is to say, taking for example a restaurant, it is customary in many such places to have a fixed minimum charge and to make all other charges multiples thereof, 20 there being, for instance, in some restaurants, no charge that is not five cents or some multiple thereof, and it is customary in some places to furnish each waiter with a bundle or pad of checks fastened together 25 at one end and adapted to be torn off in sections, each section carrying inscriptions of the amounts of possible charges as, 5, 10, 15, etc., cents. It is found, however, that considerable width, say a quarter of an inch 30 lengthwise of the check, more or less, should be allowed to each section or the sections would be inconvenient to handle and too difficult to tear off accurately, and it is therefore pertinent that when many of such 35 charge indicating marks are arranged in a column on the check strip with one charge on each section that the length of the strip will be excessive and the pad will be inconvenient to carry.

It is well known that in a great number of restaurants, barber shops and other places dealing in numerous small services, that a great majority of the charges for any one service does not much exceed fifty cents and 45 that if a check strip is made to read as high as sixty cents it will meet the requirement of a very large proportion of the transactions which are liable to occur; but that the charges forming exceptions to this general

rule may greatly exceed the limit of sixty 50 cents or even of one dollar.

It is evident that if the check constructed in sections one quarter inch wide for each item of charge, were made to cover transactions extending up to one dollar that the 55 strip must necessarily exceed five inches in length, and it is found in practice that another inch is necessary in order to give room for a suitable heading and for the stub, and it is found that a pad six inches in length 60 affords a very practical convenient size to handle but it is evident that with such a check no provision is made for any amount equal to one dollar.

An object of this invention is to avoid 65 these difficulties and to provide a check which is adapted within itself to indicate any of the charges from the minimum to any multiple thereof, within a desirable maximum, as the sixty cents just suggested, 70 so that the record is made and information given by simply tearing off the appropriate portion of the check and delivering it to the customer; and it is an object to so construct said check that it is automatically 75 protected from being lowered by the customer or the cashier and so that it affords means whereby they can be apprised of any charge and the waiter can retain on his stub a memorandum by which he can protect his 80 own accounts with the cashier and the kitchen.

This is accomplished by means described and more particularly set forth in the subjoined detailed description.

The accompanying drawings illustrate 85 the invention:

Figure 1 is a view of a pad of checks manufactured and constructed in accordance with this invention and ready for use.

Fig. 2 is a view of the pad shown in Fig. 1 after one of said checks has been removed for a charge less than the maximum printed charge on the strip.

Fig. 3 is a view of said pad after another 95 of said checks has been used to indicate a charge greater than the maximum printed charge on the strip.

Fig. 4 is a view of the customer's bill after its detachment from the pad in Fig. 2.

Fig. 5 is a view of the customer's bill after its detachment from the pad shown in Fig. 3.

The pads *x* are formed of strips *y*, *y'*, *y''* and so on, and each strip is composed of a waiter and sales stub *a*, to which a fastener which may be an ordinary staple *b* is applied for the purpose of fastening the bundle of strips together, a sectional body *c* and a cashier's tab *d*. The sectional body *c* is interposed between the stub *a* and the tab *d* and is made integral therewith but is partially separated, and is easily separable therefrom by scores *e*, *f* which may be lines of perforations, and the stub *a* and tab *d* are provided with and bear duplicate identification marks *g* or characters, so that when the body portion *c* is torn at the score *e* from the stub *a*, it and tab *d* thereon, may answer the purpose of a check to be delivered to the purchaser and by him to the cashier, and the identification marks *g* serve to identify the check thus delivered with the service for which it was given.

Said body *c* is divisible into a clerk's memorandum *c'* and a customer's bill *c''* and is provided with scores *h* practically separating said memorandum and bill into a plurality of sections *i*, and the sections are provided with charge indicating marks or characters *j* respectively which, in the instance shown, consists in the characters 5, 10, 15, 20, 25, 30, 35, 40, 45, 50, 55 and 60, each of which occurs only once upon the check so that if the charge is any amount from five cents to sixty cents, with the uniform difference of five cents between any two successive charge characters, the charge may be indicated on the check by simply tearing at such a score *h* as to leave at the torn end of the detached portion, which constitutes the customer's bill the character designating the appropriate charge, see Fig. 4. Thus the body is provided with a single column of numbers and is designed to be severed transversely between any two adjacent numbers into a memorandum and a bill, the numbers on the memorandum increasing from the stub toward the line of severance and the numbers on the bill decreasing from the tab toward said line of severance. On the stub and tab there are arranged charge bordered spaces *k* which preferably comprise a "number served" space *l* and an over amount space *m* which are appropriately marked with designating marks *n* and *o* to indicate their uses. The tab also carries the marks *p* to indicate the place of the payment.

In practical use when only one customer is served and the charge does not exceed sixty cents the waiter or salesman simply

detaches from his pad the cashier's tab and so much of the body *c* as is necessary to leave at the end thereof the section bearing the charge character *j* which designates the amount of the charge and when he has given the same to the person served his further attention thereto is not needed until the time of final settlement at which time the largest amount attached to the pad stub indicates within five cents the charge made and indicated on the torn end of the detached portion of the body *c*, but if more than one person is served, the attendant will apply in both the "number served" spaces *l* character indicating such number served. It is seen that by arranging the minimum charge character nearest to the stub and farthest away from the tab, and the other charge characters in a single column with and successively from the minimum charge character, so that the maximum charge character is farthest away from the stub and nearest to the tab, the charge character *j* on the end section of the customer's bill is automatically protected from being lowered, as by tearing off this section which indicates the amount to be paid, the bill will be raised instead of lowered. If the amount of the charge is in excess of the highest charge number found in the body *c* the attendant will apply in the "over amount" space *m*, characters as at *g* indicating the charge, see Fig. 3.

When an over amount check is thus given by the waiter there is left on his stub the clerk's memorandum check *c'* so that if he by chance neglects to write on his stub the amount of the over amount check he will still have a reminder that will direct him to the cashier where he can find and then fill in on his stub the amount.

I claim:

A waiter and sales check comprising a strip composed of three main sections; namely, a stub provided with identifying characters thereon, a tab having identifying characters in duplicate of the characters on the stub, and an intermediate body section; a transverse score between the stub and the intermediate body section; another transverse score between the intermediate body section and the tab; a plurality of transverse scores spaced predetermined distances apart from said other scores and from one another upon said intermediate body section; each of the scores being adapted to make the strip easily separable at the score; a charge number between each two scores, each charge number occurring only once upon the check, the minimum charge number being arranged nearest to the stub and farthest away from the tab, the other charge numbers being arranged in a single column with and successively from the minimum charge number,

so that the maximum charge number is farthest away from the stub and nearest to the tab, the difference in value between any two successive charge numbers being uniform and the stub and the tab each having a bordered space thereon for registering therewithin any amount in excess of the maximum charge number upon the intermediate body section, said bordered spaces be-

ing properly marked in order to indicate 10 their purpose.

In testimony whereof, I have hereunto set my hand at Los Angeles, California, this 22d day of April, 1913.

WILLIAM C. DILLINGHAM.
